DESIGN FOR A COMBINATION DESK UNIT

Earl C. Gilman, Kansas City, Mo.

Application May 8, 1944, Serial No. 113,515

Term of patent 14 years

(Cl. D74—1)

To all whom it may concern:

Be it known that I, Earl C. Gilman, a citizen of the United States, residing at Kansas City, in the county of Jackson and State of Missouri, have invented a new, original, and ornamental Design for a Combination Desk Unit, of which the following is a specification, reference being had to the accompanying drawing, forming a part thereof.

Fig. 1 is a front perspective view of a combination desk unit, showing my new design.

Fig. 2 is a rear elevational view thereof; and
Fig. 3 is an end elevational view thereof.

I claim:

The ornamental design for a combination desk unit, as shown.

EARL C. GILMAN.
